UNITED STATES PATENT OFFICE.

HENRY C. STRUCHEN, OF ST. PAUL, MINNESOTA.

GUIDE-BAR SUPPORT FOR CONCRETE-GAGES.

1,212,843.

Specification of Letters Patent. Patented Jan. 16, 1917.

Application filed February 21, 1916. Serial No. 79,574.

To all whom it may concern:

Be it known that I, HENRY C. STRUCHEN, a citizen of the United States, residing at St. Paul, in the county of Ramsey and State 5 of Minnesota, have invented new and useful Improvements in Guide-Bar Supports for Concrete-Gages, of which the following is a specification.

My invention relates to improvements in 10 guide-bar supports for concrete gages.

Under the present system of constructing concrete floors, it is difficult to level the surfaces thereof and thereby secure uniform thickness. It is not unusual to find a variation 15 in thickness of two inches in such floors, which variation, of course, entails loss of economy in construction and defects in the completed structure.

It is the object of my invention to provide 20 an inexpensive and easily used device to remedy these defects.

A further object is to provide a gage of this kind, which may be removed from the floor before the concrete is set and used 25 again, or it may be depressed in the floor, after it has served its purpose as a gage, and used as a hanger as hereinafter described.

In the drawings, Figure 1 is a perspective view in detail illustrating a number of gages as used in the construction of a concrete floor; Fig. 2 is a detail sectional view 30 showing a gage embedded in the floor and serving as a hanger for objects therebeneath; Fig. 3 is a perspective view in detail illustrating my preferred form of gage; Fig. 4 is a similar view showing a modified form thereof; and Fig. 5 is a plan view illustrating 35 a blank from which my improved gage is formed.

Having reference to the drawings, it will be seen from Fig. 5 that the blank from which my gage is constructed is a strip 10 of sheet metal. The lower end of said strip 40 is pointed by cutting away the corners on the dotted lines 11 and a perforation 12 is punched near said lower end, as indicated by the dotted circle. The strip 10 is also cut near its upper end on the dotted lines 50 13, said cuts extending inward from opposite edges of the strip, then downward, as shown in said Fig. 5. These cuts form arms 14, which are bent outward, then upward, to adapt them to receive a guide bar. The upper 55 end of the strip 10 provides a head to

receive the blows of a hammer when the gage is driven into a form, and the metal in the outer margins of said head above the arms 14 provides pliable retaining clips 15, which may be bent laterally over the guide 60 within said arms. Said clips 15 also form projections which may be engaged by the claws of a hammer or crowbar in pulling the gage from the form into which it is driven. A central longitudinal corrugation 16 is 65 formed in the strip 10 to strengthen the gage, and said corrugation converges at its lower end toward the point of said gage to facilitate the driving of the same into the floor of the form.

The modified form of my gage, shown in Fig. 4, is identical with the preferred form, already described, except that the arms 14 and retaining clips 15 are offset upon opposite sides of the strip, instead of being offset 70 upon the same side as in the preferred form.

In use, as will be seen by reference to Fig. 1, several of my improved gages are driven to the desired depth at convenient intervals into the floor 17 of a form, into which concrete is to be poured. Guide bars 18 are placed in the arms 14 of said gages and the clips 15 are turned over the upper edges of said bars to retain the same in said arms. The concrete is then poured into the form 80 and surfaced by a leveler 19 which is moved upon the bars 18. If it is desired to again use the gages, they are withdrawn from the form before the concrete becomes hard, but if it is desired to employ the gages as hangers beneath the floor, they are (after they have served their primary purpose) driven 85 below the surface of the floor and allowed to become set in the concrete as the same hardens. To embed the head of the gage in 90 the concrete floor for such secondary use, the point is driven through the form and when said form is subsequently removed, the perforated end of said gage is accessible 95 beneath the floor for use as a hanger for pipes or other fixtures.

My modified form of gage is particularly adapted for use at points where the ends of the guide bars 18 overlap, but my preferred form may be used in such places by employing two of said gages and arranging them back to back, the arms of one gage embracing one guide and the arms of the other gage embracing the other guide.

Having described my invention, what I

claim as new and desire to protect by Letters Patent, is:

1. A guide-bar support for a concrete gage comprising a sheet metal strip pointed at its lower end and adapted to be driven into a form for concrete floors, an arm cut and offset from said strip to receive a guide-bar and a pliable retaining clip formed by the metal at the top of the strip, said clip being adapted to be bent over the guide-bar on said arm.
2. A guide-bar support for a concrete gage formed from a strip of sheet metal pointed at its lower end and reinforced by a central longitudinal corrugation therein, arms offset from said strip and formed by cuts extending inward from opposite edges of the strip, then downward, and retaining clips above the arms to hold a guide therein.
3. A guide-bar support for a concrete gage formed from a strip of sheet metal, said strip being pointed at one end and having a central longitudinal corrugation therein, and also having supporting arms cut and offset from said strip, portions of the strip above said arms serving as retaining clips for guides adapted to be carried in said arms.
4. A guide-bar support for a concrete gage adapted to be driven into forms for concrete floors, said gage comprising a sheet metal strip pointed at its lower end and perforated near said end, said strip having an arm near its upper end to carry a guide, said arm being cut and offset from the strip, the metal at the upper end of the strip forming

ing a driving head and also forming a pliable retaining clip to hold the guide within the arm.

5. A guide-bar support for a concrete gage comprising a strip of sheet metal pointed at its lower end and having right-angled slits cut in the margins near its upper end to form arms, said arms being bent outward, then upward and together with 45 said strip adapted to embrace the lower edge and sides of a guide bar, and retaining clips at the upper end of the strip to hold the guide against upward movement.

6. A guide-bar support for a concrete gage formed from a strip of sheet metal, said strip being pointed at one end so that it may be driven into a form and having cuts at the other end to provide an arm and a head, said arm being bent to receive a 55 guide-bar, and said head providing a pliable keeper for the guide bar and also furnishing means by which the support may be withdrawn from the form.

7. A guide-bar support for a concrete gage comprising a sheet metal strip formed with a point at its lower end and a perforation adjacent thereto, said strip being adapted to be driven into a form for concrete, a supporting arm cut and offset from said strip to receive a guide-bar, and a pliable retaining clip at the top of the strip adapted to be bent over the guide-bar, as and for the purposes described.

Whereof, I have hereunto subscribed my 70 name to this specification.

HENRY C. STRUCHEN
